CECIL N. PHELPS, OF ORANGE, NEW JERSEY

MECHANISM FOR THE AUTOMATIC TRANSFER OF MAIL AND BAGGAGE

Application filed September 27, 1924. Serial No. 740,153.

This invention relates to apparatus for automatically delivering and receiving on a mail car, baggage car or the like, and afterwards ejecting therefrom at a different place, 5 a mail bag or piece of baggage, without stopping the train and without any manual operation.

An object of my invention is to provide apparatus especially adapted for transferring 10 mail from a station to a moving train and subsequently ejecting the mail from the train at a desired station.

Another object of my invention is the automatic handling and transfer of mail from a 15 crane located at a given place to a moving mail car and the subsequent automatic delivering of such mail at a predetermined station along the route.

A further object is the automatic transfer 20 of mail in a convenient and efficient manner by means of electrically operated apparatus.

A still further object is the automatic operation and control of the door on a mail or baggage car during the transfer of mail or 25 baggage to or from the car.

Other objects and advantages of the invention will become apparent as the description proceeds.

As is well known, mail and baggage are 30 generally delivered to and transferred from a car or train, either manually while the train is in motion or stopped at a station. It is clear that it would be desirable to have means for automatically delivering mail, for 35 example, to a moving train and automatically ejecting mail from said train when the proper station is reached.

According to my invention I propose to 40 automatically open the door on a mail car, while the same is in motion and approaching a station at which mail is to be collected. The means for actuating the door is preferably electrical, for example, a motor or solenoid with an iron core or armature, and is 45 energized by a collecting roller or brush on the car, or a truck thereof, contacting with a live rail or electrically energized strip on the track. When contact occurs, the actuating solenoid or motor is energized and opens the door shortly before or at the time the car

arrives at a mail crane for delivering a mail bag or pouch to the car.

The mail crane may be energized in a manner similar to that by which the car door is opened, but is preferably set by a station employee with the bag in proper position so that when the mail car arrives adjacent the crane, a contact thereon closes the circuit through a solenoid or other electromagnetic means on the crane, which in turn, releases a spring and causes the mail bag to be projected into a receptacle in the car. The car passes on further and the door is closed by another solenoid or motor, actuated in a manner similar to that in which the opening means was actuated, from another electrically-energized rail or strip.

The car then passes on until it nears a station at which the mail is to be delivered or left. The door is then opened at the desired position in the same way as before. Then the receptacle in which the mail was received is automatically tilted or moved, for example, by means of a solenoid or electric motor, to eject the mail bag or allow it to slide out of the car. Means similar to that for opening and closing the car door may be employed for ejecting the mail. After the mail bag has been ejected, the door is closed in the same way, as after the mail was received.

My invention will better be understood by referring to the accompanying drawing in which,

Fig. 1 shows in side elevation, a mail car equipped according to my invention and a mail crane or loader adjacent thereto;

Fig. 2 illustrates a plan view of the car, with the roof removed, and the mail crane adjacent thereto;

Fig. 3 illustrates a transverse sectional view of the car showing the ejector, and the mail crane adjacent thereto, shown partly in section;

Fig. 4 shows a plan of the special track used, with the wiring arrangement for effecting the actuation of the car door and loading of the mail;

Fig. 5 is a similar plan showing the wiring arrangement for effecting the actuation of the car door and unloading of the mail;

Fig. 6 is a plan view of a wind shield or deflector adapted for use with my mail crane;

Fig. 7 is a side elevation of the shield showing the manner of application to the mail crane; and

Fig. 8 is an elevational view at right angles to that shown in Fig. 7, also showing a special form of pins for holding the mail bag.

Although I have, for simplicity, illustrated my invention as embodied in a toy or miniature car and other related apparatus for effecting the desired transfer of mail, it is obvious that the same may be similarly embodied in full-size commercial apparatus in the same manner and used, not only for the transfer of mail, but for baggage and the like as well.

In Figs. 1, 2 and 3, the train or car 11 in which is embodied my invention, is provided with trucks 12 and 13, running on track 14, and a door 15. The door 15 is adapted to slide in guides 16 and 17 and is provided with opening electromagnet or solenoid 18 and closing electromagnet or solenoid 19. An iron core or armature 21 for solenoid 18 is connected to door 15 in any convenient manner, as by bolting to upright 22. The core or armature 23 for solenoid 19 is connected to door 15 in the same manner.

For energizing the solenoid 18 to open the door 15 at the proper time, a roller or brush 24 is electrically connected to the winding of solenoid 18 by conductor 25. The roller 24 is arranged to contact with a special energized rail or strip 26. The other end of the solenoid winding is grounded by means of the conductor 27.

The winding of the solenoid 19 is similarly connected to roller or brush 28 by means of conductor 29. The other end of the winding is grounded at 30. Grounded roller 31 is provided for operating the mail crane, hereinafter more fully described, to load mail on the car.

For receiving and discharging mail, the car 11 is provided with an unloader or ejector 32, preferably scoop-shaped as shown. The ejector 32 is pivoted at 33, so that it may be either held horizontally, as shown, or tilted to eject or discharge mail or baggage. An electric motor, electromagnet or solenoid 34 is preferably provided for unloading the mail or baggage delivered to the ejector 32. A core or armature 35 for this solenoid is connected to ejector 32 by rod 36, pivoted thereto at 37. The winding of the solenoid 34 is connected to roller or brush 38 by means of conductor 39. The other end of the winding is grounded by means of conductor 40. The roller 38 may be resiliently held against its cooperating live rail or strip, later described, by means of spring 41. This also applies to the other collecting rollers or brushes.

The mail crane or loader 42, preferably comprises a base 43 and a standard 44. The mail bag holder 45 preferably comprises a vertical member 46 provided with two pins 47 holding the mail bag or pouch 48. A horizontal member 49 of the holder 45 is slidably supported in slots 51 of standard 44. For throwing the bag 48 into the car 11, a spring 52 is provided surrounding the member 49, between the member 46 and the standard 44.

When set for throwing the bag into the car, the spring 52 is compressed between the vertical member 46 and the standard 44, by the engagement of a pin 53 with a catch 54 on the horizontal member 49. When the pin 53 is released, the bag holder is stopped at the end of its normal path of travel by the engagement of nib 55, on member 49, with standard 44. The lower portion of the slots 51 are provided with channels 56, allowing the catch 54 to pass through the standard 44 when the bag 48 is moved.

The bag holder 45 is preferably automatically released, for throwing the bag 48 into the car 11, by means of an electromagnet or solenoid 57 positioned in the base 43 of the crane. The solenoid 57 is connected to binding posts 58 and 59 (Figs. 1 and 2) in any desired manner, for example, by means of conductors 61 and 62, so that the crane or loader may be automatically actuated, as more fully described hereinafter. When energized through conductors 61 and 62, the solenoid pulls core or armature 63 downward. Core 63 is preferably flexibly connected by means of a wire 64 to actuating member 65, slidably mounted in bearings 66 and 67, for vertical movement in the standard 44. Member 65 is provided with a horizontal arm 68, which extends out of standard 44 through slot 69, of sufficient size to permit the desired limited movement. Upon arm 68 is mounted the pin 53, before mentioned.

For holding pin 53 normally in engagement with catch 54, a spring 71 is provided, supported from standard 44 by means of bracket 72 and pin 73.

The track arrangement and wiring is illustrated in Figs. 4 and 5, in which 74 and 75 are the main rails on which the car wheels travel. These rails, in the embodiment shown, are supported on metal ties 76 and may be considered as grounded. The live or third rail 77 is centrally located in this embodiment and supplies current to the locomotive in the usual manner. It is shown connected to one terminal of the secondary winding 78 of transformer 79 by means of conductor 81, the other terminal being connected to main rail 75 by conductor 82, although it is obvious that conductor 82 may be connected to a metal tie 76 or to the other rail 74, instead of rail 75. The third rail 77 is insulated at 83 from the ties 76, as shown. The primary winding 84 of transformer 79

is connected to a suitable source of electricity by means of switch 85. For a toy as an example, 110 volt alternating current from a lighting circuit, may be stepped down by transformer 79 to about 19 volts.

5 Auxiliary rail or strip 26 for supplying electricity to brush or roller 24 on car 11, to open the car door, is supported between rails 75 and 77 and insulated at 86 from the ties. 10 It may be energized by connecting it directly to third rail 77 by conductor 87, as shown, or may be directly connected to a suitable source of energy in any desired manner. Both ends of this rail 26 are preferably beveled or rounded off, as shown at 88, to permit easy engagement and disengagement with the roller 24. The left hand end of rail 26 is shown broken away.

15 Auxiliary conductor 89, for supplying current to the crane 42, to actuate it, is preferably supported outside of rail 75, insulated therefrom as shown at 91 and beveled or rounded off at both ends, as shown, at 92. It is adapted for engagement with roller 31 and is shown broken away at its right hand end. Conductor 89 is connected to binding post 59 of crane 42. The other post 58 is connected to left hand terminal of secondary 78 of transformer 79 by means of conductor 93.

20 For closing the car door after the mail has been received, conductor 94 is provided supported outside of the rail 74, in the embodiment shown, and insulated therefrom as shown at 95. It is beveled at both ends, as shown, at 96 and adapted for engagement with roller 28 of car 11. It is energized in any suitable manner, as by conductor 97 from third rail 77. This completes the description of the track apparatus shown in 25 Fig. 4 for effecting the opening of the car door, the loading of mail therein and the subsequent closing of the car door.

30 In Fig. 5 is shown a similar rail or conductor 26' for opening the car door at another station where the mail is to be unloaded or ejected. This rail is constructed and connected similarly to rail 26 so that further description is unnecessary.

35 Auxiliary rail 98 is provided for cooperation with roller 38 to unload or eject the mail at the proper station. It is beveled at both ends as shown at 99. It is insulated from the ties as shown at 101 and the right hand end is shown broken away. It may be energized in any suitable manner as by being connected with third rail 77 through conductor 102.

40 For closing the car door after the mail has been ejected, a conductor 94' is provided. As this conductor is constructed and connected similarly to conductor 94 of Fig. 4, further description thereof is unnecessary.

45 The wind shield or deflector 103 shown in Figs. 6, 7 and 8, may be used with the mail crane 42 to prevent wind storms or the like from disturbing or removing the mail bag

from the crane. It may comprise two plates 104 joined by a cross piece 105. The cross piece 105 is provided with an aperture 106, adapted to fit over the knob 107 on the top of the mail crane standard 44 and the plates 104 are preferably provided with means to prevent their turning, for example, with slots 108 engaging binding posts 58 and 59 or other suitable elements on the base of the crane. The deflector is so positioned that the bag holder and bag are approximately midway between the plates 104.

50 As shown in Fig. 8, the pins for supporting the mail bag may be formed as shown at 47' with depressions 109 therein to more securely hold the bag in position. I term pins formed as here shown, "semi-locking".

55 The operation of the aforescribed apparatus is as follows. The crane 42 is set as shown in Fig. 3 with the mail pouch 48 held in position on the pins 47. That is, the spring 52 is compressed by moving the mail bag holder 45 toward the standard 44 until the catch 54 is engaged by the pin 53 and the holder 45 thereby locked in retracted position. The mail car 11 moves on the track 14 toward the station at which the mail crane 42 is located. As it approaches this station and the crane 42, the roller or brush 24 on the car 11, engages the energized rail 26 and causes the door 15 to open.

60 This door 15 is opened because of the energization of solenoid 18 which causes core 21 attached to said door, to be drawn to the left. The circuit causing the energization of the solenoid 18 when roller 24 engages energized rail 26, is as follows. From left hand terminal of transformer secondary 78, through conductor 81, third rail 77, conductor 87, energized rail 26, roller 24, conductor 25, solenoid 18 to ground at 27. In this connection it should be noted that the right hand terminal of secondary 78 is grounded by being connected to main rail 75 through conductor 82. This completes the circuit back to the transformer secondary 78; it being understood that in grounding one terminal of the solenoid 18, the same may be connected to any part of the car in electrical contact with the wheels so that the ground circuit is completed through the wheels to the main rails 74 and 75.

65 After the door has been opened as aforescribed, the car in traveling further, causes the engagement of roller or brush 31 thereon, with conductor 89, thereby energizing solenoid 57 in the base of crane 42, releasing the mail bag and causing it to be thrown into the car through the open door and deposited on the scoop-shaped ejector 32.

70 The circuit for energizing the solenoid 57 is as follows. From the left hand terminal of secondary 78, through conductor 93 to binding post 58, through conductor 61, through solenoid 57, through conductor 62

to binding post 59, from there to conductor or energized rail 89, to roller 31 and from thence to ground; that is, through the car wheels to the main rail 75 and from thence back to the transformer secondary 78 through conductor 82.

Upon energization of the solenoid 57, the armature or core thereof 63, is drawn downwardly, thereby pulling sub-armature 65 through flexible wire 64 against the action of the spring 71, normally holding the pin 53 in engagement with the catch 54 to hold the spring 52 in compression. When, however, the sub-armature 65 is drawn downwardly, upon energization of the solenoid 57, the pin 53 disengages and releases the catch 54, allowing the spring 52 to throw the bag holder 45 toward the car. This also projects the mail bag 48 in the same direction and upon the bag holder 45 being stopped by the engagement of the nib 55 on the standard 44, the bag 48 is disengaged and thrown into the car through the open door and caught by the ejector 32. The energized rail or conductor 89 is so positioned with respect to the location of the crane, the speed of the train or mail car and the time element of the solenoid 57 and crane 42, that the open car door arrives directly opposite the crane 42, just as the mail bag is being projected therefrom.

The conductor 89 is preferably made movable or adjustable in any desired manner, by clamping, for example, so that the operation of the crane may be accurately timed for a given value of these factors and the rail moved to correspond with any change in one or more factors. For given constant values of these factors, the conductor 89 may be positioned by calculation, but more readily by trial. That is, the conductor may be tentatively set at the apparent proper position and the car moved past it on the track, at the desired speed. If the mail bag is projected and hits the side of the car towards the front of the car, for example, it is obvious that the conductor engages with the roller 31 too soon and must therefore be moved toward the direction of car travel, a distance corresponding to the misplacement of the bag with respect to the car door. If, however, the misplacement is the other way, the conductor must be moved, in the opposite direction, a corresponding distance.

The other rails or conductors 26, 94, 26', 98 and 94' need not be made movable, as it is not essential that they be as accurately positioned, the operation of their connected devices not being as critical as that of the crane 42. That is, the door-opening, conductors 26 and 26' can operate in plenty of time before the crane is reached, the door-closing conductors 94 and 94' can operate after allowing plenty of time for the mail bag to be received or ejected and plenty of time can be allowed

for the operation of the ejector 32, while the door is open.

When this is accomplished, the car 11 travels further until the roller 28 engages the conductor or energized rail 94. This causes the solenoid 19 to be energized and as the car has traveled so that the roller 24 has become disengaged from the energized rail 26, the solenoid 19 attracts the core 23, pulling it to the right and closing the door, as will be apparent from an inspection of Figs. 1 and 2. The circuit for effecting this operation is as follows. From left hand terminal of secondary 78, through conductor 81 to third rail 77, through conductor 97 to conductor 94, through roller 28 and conductor 29 to solenoid 19 and from thence to ground; that is, through the wheels back to main rail 75 and to right hand terminal of secondary 78 through conductor 82. This places the car in the same condition that it was previous to the aforescribed operations except that it contains the mail bag 48, or other article which it was desired to transfer thereto, and it has all this time been travelling at the desired rate of speed along the track.

The car 11 continues its travel until it comes to another station at which it is desired to leave the mail bag, transferred to it, or any other mail bag or article that has been or may be placed in the ejector 32. The track arrangement at the station at which it is desired to eject the mail bag is represented at Fig. 5. As heretofore described in connection with Fig. 4, upon reaching the track represented in Fig. 5, the roller or brush 24 first engages the live rail 26' and this again effects the opening of the door 15 on the car in the same manner as heretofore described, as the connections for rail 26' are the same as for rail 26.

The door having been opened, by engagement with rail 26', the car on traveling further, causes roller or brush 38 to engage auxiliary energized rail 98 to effect the energization of solenoid 34, to operate the ejector 32 and discharge the mail bag or other article from the car 11. The circuit for effecting this operation is as follows. From the left hand terminal on secondary 78, through conductor 81 to third rail 77, from thence through conductor 102 to energized rail 98, to roller 38, through conductor 39 to solenoid 34 and from thence to ground, or through the car wheels to main rail 75 and back to the transformer secondary 78 through conductor 82. The energization of solenoid 34 causes its armature or core 35 to be drawn therein, thereby pushing rod 36 to the left, as shown in Fig. 3, and raising the ejector 32 about its pivot 33. The ejector is raised to an elevation sufficient to cause the bag 48 to slide therefrom out of the car and be deposited at the desired station.

After this has been effected, the car passes

along the track until roller 38 disengages from the energized rail 98 and ejector 32 is released and drops back into the position indicated in Fig. 3. The car on traveling further, causes the roller 28 thereof, to become engaged with energized rail or conductor 94' to thereby effect the closing of the door 15 again, in the same manner in which it was previously closed, by the engagement of said 10 roller with conductor 94, as the connections to 94' are the same as those to conductor 94.

The foregoing is a description of a complete cycle of operations whereby a mail bag or other article is automatically transferred 15 from the crane to a moving mail car or train and automatically ejected at another station. While this is being accomplished, the side door of the mail car is automatically opened and closed at the proper places so that it only 20 remains open when the mail bag or other article is being transmitted to the car or ejected therefrom.

Although the crane for transferring the mail bag to the car has been described as being 25 released by the energization of a solenoid so that a spring transfers the mail into the car, it is obvious that electrical means may be used for directly transferring the mail into the car without the use of a spring for this 30 purpose. That is, instead of the solenoid merely releasing the spring, it or some other electrical machine, may actually cause the mail bag to move into the mail car.

The mail crane shown in this embodiment 35 is arranged to be set by hand, by compressing the spring 52 until the catch 54 engages the pin 53, but it is obvious that any desired means may be employed for compressing the spring if the same is embodied in a commercial machine rather than in a toy, as illustrated, and therefore too strong to be conveniently set by hand.

Although I have illustrated solenoids for 40 effecting all the desired automatic movements of the door, crane and ejector, it is obvious that I do not wish to be limited thereto as when my invention is embodied in a full size commercial car and auxiliary apparatus, it may be desirable to use other electrical devices, such as motors, for effecting the desired 50 operations, rather than solenoids.

I have described what is now considered a preferred embodiment of my invention in the form of a toy, but it is obvious that the same 55 is merely illustrative and that other embodiments thereof may be made both for the purpose of toys and also for full sized commercial apparatus for effecting the automatic transfer of United States mail or other articles, within the spirit and scope of my invention as defined by the appended claims.

What is claimed is:

1. In combination, a track, a railway car 60 thereon having a sliding side door, an armature connected to said door, a solenoid in en-

gagement with said armature for effecting the automatic opening of the door at a given position, a machine located near the track on which the car travels and provided with means for holding a mail bag or other desired object and means for throwing said object into the car and electrical means for releasing said throwing means and adapted to be automatically operated by the movement of the car to cause the mail bag to be transferred to the car at the proper time.

2. In combination with a railway car movable on tracks, a slidable door in a side thereof, electrical apparatus connected to said door for opening the same at a desired station, said apparatus being actuated by the engagement of a contact member on the car with an energized rail on the track to thereby connect said apparatus with a source of electrical energy and power means positioned adjacent the track and operated electrically by the engagement of a contact member on the car with a conductor positioned on the track to cause an object to be automatically delivered to the car through said door after the opening thereof, when said car is properly positioned with respect to said power means.

3. In combination, a car having a door, means for automatically opening the door, means for automatically delivering an object to said car after the door has opened and electrical means for automatically closing the door after the object has been delivered.

4. In combination, a track, a railway car thereon having a sliding side door, an armature connected to said door, a solenoid in engagement with said armature for effecting the automatic opening of the door at a given position, a machine located near the track on which the car travels and provided with means for holding a mail bag or other desired object and means for throwing said object into the car, electrical means for releasing said throwing means and adapted to be automatically operated by the movement of the car to cause the mail bag to be transferred to the car at the proper time and another solenoid adapted to operate another armature connected to the car door to close said door after the mail bag has been delivered to the car.

5. In combination with a railway car movable on tracks, a movable door in a side thereof, electrical means for opening the door at a desired station, means outside of the car operated electrically for delivering an object through said door after opening and while the door is properly positioned with respect to said delivering means and electrical means for closing the door after the object has been delivered, all of said means operating while the car is in motion.

6. In combination with a railway car movable on tracks, a slidable door in a side there-

- of, electrical apparatus connected to said door for opening the same at a desired station, said apparatus being actuated by the engagement of a contact member on the car with an energized rail on the track to thereby 5 connect said apparatus with a source of electrical energy, power means positioned adjacent the track and operated electrically by the engagement of a contact member on the car 10 with a conductor positioned on the track to cause an object to be automatically delivered to the car through said door after the opening thereof, when said car is properly positioned with respect to said power means and 15 electrical means for closing the door after the object has been delivered to the car, said means being energized by the engagement of a roller or brush on the car with an energized rail on the track, all of said means operating automatically while the car is in motion. 20
7. In apparatus for effecting the automatic transfer of mail and the like, the combination of electromagnetic means on a car for opening a door thereof, electromagnetic means positioned along the track for effecting 25 the transfer of mail or the like to said car at the proper time while the door is opened and electromagnetic means for causing said door to close upon the transfer of said mail or the like to the car. 30
8. In combination, a car having a sliding door, means for automatically opening the door, a trough-like article holding device pivotally mounted in the car, means for automatically 35 tilting said device to allow an object therein to slide from said car after said door has been opened and means for automatically closing the door after said object has been ejected. 40
9. In combination with a railway car movable on tracks, a movable door in the side thereof, electrical means for opening the door at a desired station for ejecting an object therefrom, electrical means for ejecting the object from said car after the door has been 45 opened and electrical means for again closing the door after the object has been ejected. 50
10. In apparatus for effecting the automatic transfer of mail and the like, the combination of electromagnetic means on a car for opening a door thereof, a receptacle for mail or the like, electromagnetic means on said car for tilting said receptacle and ejecting the contents therefrom and electromagnetic means on said car for again closing the door after said mail or the like has been ejected from the car. 55
11. A railway car containing a pivoted scoop-shaped member, a solenoid associated therewith, an armature for said solenoid, a rod connecting said armature to said scoop-shaped member, a collecting roller on the car adapted for engagement with an energized rail along the track and electrically connected with said solenoid, whereby when

the car reaches a desired position, the solenoid is energized and moves its armature to effect a tilting of the scoop-shaped member. 60

12. A railway car comprising a member for collecting and ejecting articles, arranged adjacent a slidable door in the side of the car, electrical means for automatically opening said door when said car merely reaches a desired location on the track, electrical means for automatically tilting said member to eject an article from said car when the door is open and electrical means for automatically closing said door after the article has been ejected. 70

13. In a track for effecting the automatic transfer of articles to moving trains, an auxiliary rail suitably energized and positioned so that the door of a railway car moving on said track is opened by the closing of a circuit therethrough, a second energized rail for effecting the transfer of an article from a crane positioned along the track to a moving train at the desired position after the door is opened and a third energized rail for effecting the closing of the door after the article has been delivered. 80

14. A track arrangement for effecting the automatic transfer of articles to moving railway trains comprising a plurality of energized rails spaced longitudinally along the track so that first a circuit is closed through apparatus of a moving car by engagement with the first rail to effect the opening of a car door, then a transfer of an article from apparatus positioned adjacent the track to the car is effected by a circuit through a second rail and a third rail so positioned to effect the closing of said car door after the article has been delivered thereto. 90

15. In combination, a car having a door, electrical means on the car for automatically opening the door upon the mere movement of the car to be a predetermined position to complete an electrical circuit and means outside of the car disposed adjacent said position for automatically delivering an object to said car after the door has opened and another circuit completed. 105

16. In combination, a car having a door, means in the car for automatically opening the door upon the mere movement of the car to a desired location and the completion of an operating electrical circuit while the car is in motion and electrical means disposed along the path of movement of the car and in circuit with the car for automatically delivering an object to said car through the open door while the car is in motion. 115

17. In combination, a car having a door, electrical means carried by the car for automatically opening the door at a desired location while the car is in motion, means outside of the car but operated by the completion of an electrical circuit through the car for automatically delivering an object to said car 125

through the open door while the car is in motion and other means carried by the car for automatically closing the door after the object has been delivered while the car is in motion upon the mere continued movement of the car a predetermined distance.

5 18. In combination, a car having a floor and a side wall, a door in said wall, a trough-like device pivotally mounted in said car, the pivot means for said device being disposed so near the floor and door of the car that an object therein will slide out of the door upon tilting the device, and means carried by said car for automatically tilting said 10 device to allow an object therein to slide from said car at a predetermined position.

15 19. A railway car comprising a slidable door in the side of the car, a member for collecting and ejecting articles, arranged adjacent said door, electrical means on the car 20 for automatically opening said door upon movement of the car causing the completion of an electrical circuit thereto and means carried by the car for automatically tilting said 25 member to eject an article from said car when the door is open.

20 20. In combination with a railway track, three energized rails disposed longitudinally therealong and adapted for engagement with 25 circuit making means depending from a car traveling on said track, so that upon movement of the car to the first rail, a circuit is closed through apparatus on said car by engagement of circuit making means associated 30 with said apparatus to effect the opening of a car door, then an article is ejected by engagement of other circuit making means on the car with the second rail to close a circuit through an ejecting device on the car, and 35 lastly, another circuit making device on the car engages the third rail and effects the closing of a circuit through other apparatus on the car to cause the door to close after the 40 article has been ejected.

45 In testimony whereof, I have hereunto subscribed my name this 22nd day of Sept., 1924.

CECIL N. PHELPS.
